A. H. SASS

CONDENSER

Filed May 11, 1922

Inventor:
Adolph H. Sass,
by Joel L. Palmer, Atty.

UNITED STATES PATENT OFFICE.

ADOLPH H. SASS, OF MOUNT VERNON, NEW YORK, ASSIGNOR TO WESTERN ELECTRIC COMPANY, INCORPORATED, OF NEW YORK, N. Y., A CORPORATION OF NEW YORK.

CONDENSER.

Application filed May 11, 1922. Serial No. 560,000.

To all whom it may concern:

Be it known that I, ADOLPH H. SASS, a citizen of the United States, residing at Mount Vernon, in the county of Westchester, State of New York, have invented certain new and useful Improvements in Condensers, of which the following is a full, clear, concise, and exact description.

This invention relates, in general, to condensers and more particularly to condensers of the variable type.

In the common type of variable condenser in which air is used as a dielectric, it is necessary to provide a very small separation between opposing plates in order to obtain a condenser of suitable capacity and one which is not unnecessarily large in size. It is, therefore, necessary to space the opposing plates very accurately in order to insure the necessary clearance. It has been the common practice heretofore to mount the movable plates and the fixed plates of such condenser on separate mountings and to employ spacers for insuring a given separation between the plates. However, with such a construction employing a large number of plates, it is difficult to insure the correct spacing between all plates, even though working to very close mechanical limits since the effect of a slight error in the thickness of the spacers is cumulative and becomes highly objectionable where a large number of plates are employed.

It is an object of the present invention to provide a variable condenser in which the desired separation between plates can be obtained without working to unnecessarily close limits.

It is another object of this invention to provide such a structure which is cheap of manufacture and the electrical constants of which will not change materially under service conditions.

To accomplish these objects, and in accordance with a feature of the invention, there is provided a condenser in which both the movable plates and the fixed plates are supported on the same shaft and the distance between adjacent plates is determined by spacing means. In accordance with another feature of the invention, the outer portions of the plates are so supported as to prevent any appreciable change in the spacing therebetween.

These and other features of the invention will be more clearly understood by reference to the drawing in which Fig. 1 is a plan view of a condenser embodying the features of this invention; Fig. 2 is 60 an elevation partially in section of the condenser of Fig. 1; Fig. 3 is a view of one of the fixed plates; Fig. 4 is a view of one of the movable plates; and Fig. 5 shows the manner in which the outer edges of the 65 plates are supported.

The drawings show a plurality of fixed plates 5, 5 mounted alternately with a plurality of movable plates 6, 6 upon a rotatable shaft member 7. Rigidly secured 70 to the shaft 7 is a square insulating bushing 8 which is preferably molded in position, but may be fastened to the shaft by means of key ways or by pinning. The fixed plates 5, 5 are provided, as shown, 75 with circular perforations 9 of suitable diameter to permit the plates to rotate freely about the bushing 8, the corners of which are preferably rounded slightly as shown. One of the fixed plates is provided with 80 angular extensions 10, 10 for mounting purposes as will be explained hereinafter. The movable plates 6, 6 are provided with square openings, suitably dimensioned to permit the plates being assembled upon the bushing 8.

In assembling the structure, an end plate or washer 11 is threaded over the lower portion of the shaft until it strikes a shoulder portion (not shown in the drawing). 90 Movable plates 6, 6 are then threaded upon the shaft alternately with fixed plates 5, 5 until the desired number of plates are provided, adjacent plates being in each case provided with spacing washers 12, 12 of 95 insulating material such as phenol fibre or hard rubber. A spring washer 13 is then placed on the end of the shaft and the plates are clamped together the desired amount by means of the nuts 14, 14. 100 Perforations or openings 15, 15 are provided in all plates to receive the U-shaped clamping members 16, 16 which are preferably of phosphor-bronze. The clamping members are sprung into position so 105 as to provide an outward tension and are preferably provided with indentations 17, 17 for accurately spacing the plates. In mounting the condenser upon a panel 18, the fixed plates are held in position by means 110

of the screws 19, which engage with the mounting brackets 10, 10 of the upper fixed plate. A knurled knob 20 is rigidly secured to the shaft to facilitate rotation and preferably a dial member 21 is also secured to the shaft.

Upon turning the knob 20, the square bushing 8 causes the rotation of the movable plates, while the fixed plates are prevented from rotating by means of the mounting brackets 10 and the clamping members 16, the bushing 8, therefore, rotating freely in the opening 9 of these plates.

15 In the structure described, the condenser plates and the separating members are preferably punched from sheet stock which can easily be held to very close commercial limits. Since the separation between adjacent plates is, in each case, controlled by a single member, no difficulty is experienced in maintaining close separation of plates thus insuring a small compact condenser for a given capacity. Moreover, the method 20 of assembling the condenser is economical and insures uniform electrical constants which do not change appreciably under service conditions.

25 The invention claimed is:

30 1. In a condenser, a rotatable insulated shaft and a plurality of parallel plates mounted thereon, alternate of said plates being rotatable with said shaft and insulated from the remainder of said plates.

35 2. In a condenser, a rotatable shaft and a plurality of pairs of parallel plates mount-

ed thereon, one of each pairs of said plates being rotatable with the shaft and insulated from the other plate of said pair.

3. In a condenser, a rotatable shaft, a plurality of electrically connected plates mounted thereon and movable therewith, and a plurality of electrically connected fixed plates mounted on said shaft and insulated from said movable plates.

4. A rotatable shaft, a set of parallel plates supported on said shaft and adapted to rotate therewith and a set of fixed parallel plates supported on said shaft and interleaving with and insulated from the plates of the first set.

5. A rotatable insulated shaft having a plurality of parallel plates mounted thereon, alternate ones of said plates being keyed to the shaft which rotates freely through the other of said plates, and electrical connections for each set of alternate plates.

6. A rotatable insulated shaft, a plurality of parallel plates mounted thereon, spacing members of insulating material separating said plates, and means to electrically connect alternate plates and to assist said spacing members in maintaining said plates in spaced relation.

7. In a condenser, an insulated shaft, a plurality of parallel movable plates, and a plurality of parallel fixed plates insulated from said movable plates, all of said plates being supported on said shaft.

In witness whereof, I hereunto subscribe my name this 6th day of May, A. D. 1922.

ADOLPH H. SASS.
